Specification of Letters Patent.

Patented Sept. 3, 1915.

Application filed January 6, 1914. Serial No. 310,082.

To all whom it may concern:

Be it known that we, FRANCIS C. CHRISTENSEN and THEODORE W. FULLER, citizens of the United States, and residents of Racine, in the county of Racine, Wisconsin, have invented new and useful improvements in Dimmers for Headlights, of which the following is a description, reference being had to the accompanying drawings, which are a part of this specification.

This invention has for its object to provide means operated from the driver's seat for reducing the intensity of the light thrown by the headlights of an automobile or the like so as to relieve the driver of an approaching car of the blinding glare and so as to be able when driving into a city to instantly comply with city ordinances prohibiting the use of strong headlights without in any way and time avoid the necessity for stopping the car to make adjustments.

With the above and other objects in view, the invention consists in the dimmer for headlights as herein claimed and all equivalents.

Referring to the accompanying drawings in which like characters of reference indicate the same parts in different views, Figure 1 is a sectional side elevation of a headlight provided with the dimmer embodying the present invention; Fig. 2 is a sectional plan view thereof; Fig. 3 is a front view of the headlight with a portion of the front glass broken away to show the burner and the dimmer; and, Fig. 4 is a detail back view of the dimmer.

The drawings 10 indicate a headlight lamp provided with the burner 11, reflector 12 and a swinging door 13 with front glass 14, all as usual. A metal clamp 15 surrounds the burner 11 near the front tip thereof and is secured firmly in place by means of its clamping screw 16 so as to afford a firm support for a swinging guard or shield 18 which is preferably of sheet metal and slightly curved laterally to effectively screen the burner 11 from the rays of light of the flame 17 of the burner. The pivotal mounting of the guard or shield 18 on the clamp 15 may be of any suitable form. As shown, the guard or shield 18 is split at its lower end to form an opening 19 to receive one of the horns of the forked burner tip, the guard or shield 18 in its upright position and thus permit it to stand close to the flame 17. The ends of the guard

or shield 18 on either side of the split portion are turned to form parallel ears 20 which fit on a pivotal pin 20 passed through a pair of parallel ears 21 on the clamp 15 and a coil spring 22 surrounds the pivotal pin 20 with one end bearing against the clamp 15 and the other end against the guard or shield 18 so as to normally hold the guard or shield in its upright position, as shown in full lines in Fig. 1, and arm 23 projects from the back of the guard or shield 18 and has a wire 24 connected thereto which passes out through the bottom of the lamp casing 10 and through a tubular conduit 25 to any suitable place within reach of the driver of the car, preferably on the dashboard.

When the wire 24 is pulled the guard or shield 18 is swung rearwardly to the position shown in dotted lines in Fig. 2 where it does not materially interfere with the rays of light from the flame 17 striking the reflector lens 12 at all parts thereof so that said guard or shield does not then interfere with the normal intensity of the light. When, however, the wire 24 is released the spring 22 returns the guard or shield 18 to its upright position where it intercepts the rays of light to the reflector and consequently diminishes the intensity of the light to a considerable degree, leaving only the direct rays of light and shutting off the reflected rays. In this condition of the headlight a sufficient light is permitted for ordinary city driving. The change from one condition to the other may be effected without the necessity for stopping the car and the device is so constructed that it may be readily attached to any headlight already in use.

While the invention is shown as applied to a gas headlight, it is obvious that the dimmer may be used with other forms of headlights without departing from the spirit and scope of this invention.

What we claim as new and desire to secure by Letters Patent is:

A dimmer for headlights, comprising a clamp for engaging a headlight burner, said clamp projecting therefrom, a concave guard or shield having a split lower end providing an opening to receive one horn of the forked burner tip of the headlight burner, the ends of the guard or shield on either side of said opening being bent to form parallel ears, a pivotal pin passing through the ears

of the burner clamp and the ears of the guard or shield, a coil spring surrounding the pivotal pin with its ends engaging the guard or shield and the clamp respectively, an arm projecting from the guard or shield, and a wire connected with the arm for swinging the guard or shield from its normal upright position in which it intercepts the rays of light to the reflector to a posi-

tion in which it is out of the path of the rays of light to the reflector.

In testimony whereof, we affix our signatures, in presence of two witnesses.

FREDERIK C. CHRISTENSEN.
THEODORE W. FULLER.
